UNITED STATES PATENT OFFICE.

BIRCHARD E. HOLTON, OF LOS ANGELES, CALIFORNIA.

AIR-BRUSH.

1,292,318.

Specification of Letters Patent.

Patented Jan. 21, 1919.

Application filed April 30, 1918. Serial No. 231,763.

To all whom it may concern:

Be it known that I, BIRCHARD E. HOLTON, a citizen of the United States, residing at Los Angeles, in the county of Los Angeles and State of California, have invented new and useful Improvements in Air-Brushes, of which the following is a specification.

My invention relates to air brushes and consists of the novel features herein shown, 10 described and claimed.

One of the principal objects of my invention is to make a material tube for delivering the material to the point of the atomizer, the tube being removable and interchangeable, so that by manipulating a set screw a tube carrying one material may be removed, and another tube carrying a different material instantly applied.

Another object of my invention is to make 20 an air brush, in which the air and material connections are both at the extreme rear end of the main head, and above the hand-hold, so as to avoid the trouble of having the hose connections dragging over the fresh work.

Another object of my invention is to make 25 a single trigger control for the air and material, and to provide adjustments so that the air will be turned on before the material is turned on, and so that the flow of material 30 may be accurately regulated.

Figure 1 is a side elevation of an air brush embodying the principles of my invention.

Fig. 2 is a sectional elevation on a plane parallel with Fig. 1.

Fig. 3 is a front elevation looking in the direction indicated by the arrows 3 in Figs. 1 and 2, parts being broken away and shown in sections, and parts being broken away to economize space.

The nozzle support 1 is cylindrical in end elevation and a bore 2 is formed from the front end face, the forward end of the bore being screw-threaded, and there being a lateral port 3 leading to the bore, and a seat 4 around the outer end of the port. The paint nozzle 5 is screwed into the bore 2, and has an orifice 6 leading through its tip, and a valve seat 7 at the inner end of the orifice, and a passage 8 leading from the bore 2 to the valve seat 7. In front of the end face of the support 1, the nozzle 5 is conical.

The air nozzle 9 is screwed upon the end of the support 1 concentric to the paint noz-

zle 5, and has an annular orifice 10 around the tip of the nozzle 5, concentric to the orifice 6. An air circulating chamber 11 is formed within the nozzle 9, around the nozzle 5 and connected with the orifice 10. Air ports 12 are drilled from end to end through 60 the support 1, in communication with the chamber 11.

The main frame 13 has a circular head 14 provided with a nipple 15, and a piece of tubing 16 fits tightly upon the nipple 15. A 65 corresponding nipple 17 is formed upon the rear end of the support 1, and fits tight in the end of the tubing 16, so as to connect the support 1 to the main frame. The main frame 13 has a housing chamber 18 extending backwardly from the head 14. A bearing 19 is formed at the rear end of this chamber. The paint valve stem 20 is slidingly mounted in the bearing 19, and extends through the chamber 18, through the head 70 14, the nipple 15, the tube 16, the nipple 17, and the bore 2, to the valve seat 7, and has a needle point 21 extending into or through the orifice 6. An expansive coil spring 22 is placed upon the valve stem 20, in the 75 chamber 18, against the forward end of the bearing 19, and engages a spring seat 23 upon the stem 20, the tension of the spring 22 being exerted to hold the needle point 21 against the valve seat 7, to stop the flow of 80 paint. A trigger 24 is pivotally mounted upon a pin 25 in the upper part of the chamber 18, and extends downwardly through the 85 wall of the chamber.

The main frame 13 has a removable side 90 plate 26, so that when the plate 26 is removed, the chamber 18 is open, as in Fig. 2, the side plate being secured in place by screws 27. The air hose 28 slips upon the nipple 29, and the nipple 29 is connected to 95 the air valve casing 30 by a union 31. The principal part of the air valve casing 30 is located within the chamber 18, there being a notch 31' in the rear wall of the main frame, so that the valve casing is placed in 100 the notch, and the plate 26 applied to hold the casing in place. Set screws 32 are inserted through the plate 26 to engage the forward end of the casing 30, and a similar set screw is inserted through the back side 105 of the frame to engage the other side of the casing 30. A valve seat 33 is formed in the valve casing 30, a valve stem 34 is slid-

ingly mounted in the casing, the forward end of the stem 34 engaging a cam 35 projecting backwardly from the trigger 24. A valve 36, upon the valve stem 34 engages a seat 33, and a spring 37 is inserted behind the valve, the tension of the spring being exerted to hold the valve closed. A chamber 38 is formed around the stem 34, in front of the valve seat 33, and a pipe 39 leads laterally from the chamber 38, through the wall of the valve casing 33, and then forwardly through the nipple 15, and into the end of the nipple 17; said pipe 39 connecting with the ports 12, leading to the chamber 11 and to the orifice 10. A U-shaped link 40 extends around the pipe 39, and has a bearing portion 41 in position to engage the spring seat 23; the ends of the link being connected to the trigger 24 by pin 41^a. A retractile coil 20 spring 42 connects the bearing portion 41 to the trigger 24, the tension of the spring being exerted to hold the bearing portion 41 against the stem 20, there being lost motion between the bearing portion 41 and the 25 spring seat 23, so that the trigger 24 may be operated to unseat the valve 33, and allow air to blow through the orifice 10, without unseating the needle 21, to open the orifice 6, and then continued operation of the trigger 30 will bring the bearing portion 41, into engagement with the valve 23, and unseat the needle 21 from the seat 7, to open the orifice 6 to the desired extent. The object being to operate both valves with a single trigger and to make it easy to use the device as a blower, and at the same time have the paint shut off, and then after the air is flowing to the desired extent, to turn on the paint as desired.

40 A set screw 43 is screwed through the wall of the frame 13, directly behind the lower end of the trigger 24, so that by manipulating the set screw, an adjustable stop is formed to accurately limit the movement of the trigger, so as to limit the opening of the paint valve. A hand-hold or grip 44 extends downwardly from the main frame 13.

45 A paint hose 45 is slipped upon a nipple 46, and the nipple 46 is secured to the paint tube 47, by a union 48.

50 A seat 49 is formed upon the upper side and rear end of the frame 13, to receive the rear end of the tube 47, and the forward end of the tube is turned downwardly and fixed 55 to fit the seat 4. A set screw support 50 extends upwardly from the back side of the frame 13, and over the seat 49, and the set-screw 51 mounted vertically through this set screw support engages a seat 52 upon 60 the paint tube 47, to hold the rear end of the paint tube rigidly in place. A second set screw support 53 extends upwardly from the sides of the nozzle support 1, upon opposite sides of the seat 4, and has a cross- 65 bar 54 through which the set screw 55 oper-

ates to engage the forward end of the paint tube 47, and hold said forward end firmly in the seat 4, so that when the set screws 51 and 55 are loosened the paint tube 47 may be removed and another paint tube substituted, so that the color or material passing through the air brush may be changed instantly, by changing the tubes, thus avoiding the necessity of washing up the old tube, and connecting a new color to it. This saves 70 a large amount of work and a large amount of material and makes the change much quicker. This construction makes it possible to place the paint hose 45 above the air hose 28, at the rear end of the main frame, 75 and at the same time deliver the material directly to the nozzle, thus avoiding the liability of the paint hose dragging over the fresh work, as in the old constructions, where the paint hose extended downwardly 80 from the nozzle.

85 Various changes may be made in the arrangement and details of construction without departing from the spirit of my invention as claimed.

90 I claim:

1. In an air brush, a main frame, a paint nozzle mounted upon the forward end of the main frame, an air nozzle mounted upon the forward end of the main frame around the 95 paint nozzle, a valve for controlling the passage of paint to the paint nozzle, a valve for controlling the passage of air to the air nozzle, a paint tube removably mounted upon the main frame and discharging into 100 the paint nozzle.

2. In an air brush, a main frame, a paint nozzle upon the main frame, a paint valve construction for controlling the paint nozzle, an air nozzle around the paint nozzle, an air valve construction for controlling the air nozzle, a paint tube mounted on top of the main frame and connected to the paint nozzle, and having a nipple adapted for connection to a paint hose, and means whereby 110 the paint tube may be removed.

3. In an air brush, a main frame, a paint nozzle mounted upon the forward end of the main frame, an air nozzle mounted upon the forward end of the main frame around 115 the paint nozzle, a valve for controlling the passage of paint to the paint nozzle, a valve for controlling the passage of air to the air nozzle; there being paint tube seats at the forward and rear ends of the top of the 120 frame; a set-screw support extending upwardly over the rear seat, a set-screw in the set-screw support, a second set-screw support extending upwardly over the front seat, a second set-screw through the second set-screw support, and a paint tube resting in the paint tube seats and removably held in place by the set-screws; the forward end of the paint tube being in communication with 125 the paint nozzle.

4. In an air brush, a main frame, a paint nozzle upon the main frame, a paint valve construction for controlling the paint nozzle, an air nozzle around the paint nozzle, an air valve construction for controlling the air nozzle, a trigger for controlling the two valve constructions, a set-screw for adjustably controlling the movement of the trigger, and a paint tube mounted on top of the main frame and connected to the paint nozzle. 10

In testimony whereof I have signed my name to this specification.

BIRCHARD E. HOLTON.
